(54) **OINTMENT, CURE OF DISEASES**

(76) Inventor: **William Waller Gray**

William Waller Gray of Richmond Virginia:

Letters Patent dated March 18th 1835.

The Schedule referred to in these Letters Patent and is a part of the same containing a description in the words of the said William Waller Gray himself of his improvement in an ointment for the cure of many external diseases

To all whom these presents shall come. To know that I, William Waller Gray of the City of Richmond in the County of Henrico and State of Virginia have invented a new and useful improvement in an ointment for the cure of many external diseases, viz. White Scutlings, Ulcers of long standing, Tumors, Eruptions, Burns, & scalds, old and fresh wounds, Catarrh, and glandular swellings &c &c, and that the following is a full and exact description of the construction and operation of said Ointment as invented or improved by me.

Receipt and mode of preparing the Ointment.

One gallon Cotton seed Oil, one gallon Linseed oil, one quart of spirit oil pern, One quart Canada Balsam, one of five two pounds of Mutton fat, one pound Bees wax and five pounds sugar of lead. The cotton seed and linseed oil to be put into an iron kettle sufficiently large to hold 14 or 15 gallons, the kettle to be hung on a fire over a fire of charcoal in a composition or other furnace, the heat of which may be regulated by opening or shutting down the furnace. The oil should be slowly boiled or diminished for five or six hours, but never so much heated as to burn or destroy the gummy substances. Previous to introducing the sugar of lead however, the heat of the oil should be considerably increased until it will scorch and blacken the feather of a hawk and the tail of a common goose quite very quickly. In this stage of the oil the lead may be introduced after being fine ground in a mortar of iron hard as fine as flour if possible, and then passed through a fine hair sieve. One person should stir the oil while another should pass the lead in small quantity through a cloth made like a pepper

ptl. after the lead is introduced, (which should require at least one hour) the
muffle and furnace must be put in and the stirring continued over
a moderate fire one half hour longer. When the heat is great and the lead
introduced it is sometimes difficult to keep the oil within the kettle
therefore by means of a crane the kettle may be very prudently removed from
the fire, and if necessary the oil may be dipped out with an iron da-
dle and put into large caustic or crockery pans, and when the heat diminishes
when the agitation subsides the oil from the pans may be returned to the
kettle, and the stirring continued until the process is completed.
After this work is done take the kettle down, let the materials get
somewhat cool, and then pour the sweet oil and Canada Balsam
(mixed together) into the ointment taking care not to let the ^{heat} to graze
as to make these last mentioned ingredients evaporate. This completes
the whole process. The ointment should then be dipped out of the kettle
strained through a fine wire sifter into crockery or glass pof pans and
then remain until the day following, when it may be rewarmed and made
sufficiently thin to be put into pots by means of a tin cup with a lip
or spout. The pots should be well corked and sealed or the ointment
will work out through every fissure. The cork should never penetrate
the mouth of the pot so far as to touch or press upon the ointment.
The tin pot mentioned above should be ^{large} enough to contain a pint
and the holes in the top made as small as that of a pepper pot.
Mode of applying the ointment. For an Ulcer, Tumor, Ulcer or Cus-
tions that discharge much matter apply fresh ointment on old linen
or cotton once in 2d Hours, but if frequently necessary in order
to remove the plaster in the course of the day and wash away the matter
discharged from the surface by the action operations of the ointment, for which pur-
sue a soft dry linen or cotton rag and be very taking care at this
some time not to wash or use water about the wound in any manner
in order to keep it under the influence of the ointment.
The discharge of matter from a sore pit wound of long standing is gen-
erally very dark at first and in some cases of this kind it may be ad-
visable to apply fresh ointment twice a day beginning and continue

order to expedite the work of cleansing as well as to subdue the inflammation and prevent mortification. When the affected part is thoroughly dressed, a disposition to heal is generally manifested by a discharge of white healthy matter, the edges becoming flat and white and the crusts falling off with small red pinches of sound flesh. In this stage of the wound apply the ointment once in 48 hours and change once in 24 as above directed. In Ulcers produced by mercury the Sarsaparilla drink should also be used in order to create a free discharge of the offensive matter. This drink can be procured of the druggists generally. For inflammations swelling, fresh wounds, sprains, or burns, once in 24 hours will be often enough to apply the ointment. If applied to the sore breast of a female it can be rendered more mild if necessary by spreading a small quantity of mittens dust on each plaster and mixing it well by heating. The materials being of the finest kind no injury whatever can arise from the use of this ointment; nor can there be the least liability to cold at any season. In relation to long standing and deeply seated sores of any kind I particularly recommend that the plasters be spread large enough to cover the whole inflamed part. in fact should the wound be situated about the middle of the leg then wrap the same in ointment from the knee to the foot until the inflammation be completely subdued, and should mortification be apprehended let the plasters be made warm in order that its effect may be rendered more active and powerful. In the snake bite this course is strenuously urged taking care first to scaly the neighbourhood of the part bitten. The spider bite is not easily treated until extended to the bone form a core and sometimes produce deep ulcerations. For sores about the breast spread a plaster large enough to cover the whole chest also apply one between the shoulders. The ointment is an excellent trophic to follow a plaster in order to create a suppuration and thereby more effectually subdue the part affected by pain particularly in cases of Ulcering. Some cases of Ulcer and sores of a tumor will require the ointment for months, perhaps before a thorough cleansing can be effected. Therefore patients and persons visitors must be accoured with great regularity in the droppings which strict attention should be paid to diet in order to prevent the system from

becoming very gross. This Oil cloth possesses three very desirable properties, viz. It subdues the inflammation, causes a free discharge of the corrupt matter and creates a healing of the affected part at the same time, while it is extremely mild in its operation. In early stages of inflammatory rheumatism, sores produced by cold (crampetic) about the breast from my own experience, this article stands unrivaled. It is sothing yet so stimulating that in the course of two hours the system is thrown into a gentle perspiration and all pain or soreness is rapidly removed. In fresh wounds the flesh being ~~cleaned~~ healing immediately takes place. In old and corrupt sores the oil cloth removes the ~~cause~~ ^{nature} and heals. In the bites of man, dog, snake and spider. I have ample evidence of its efficacy. And in all the diseases for which it is recommended its virtue has been tested under my own superintendence: and in support of it I state my upulution. A specimen of the oil cloth or mattock should be ap- plied accompanying these directions, which may be cleaned and rewrapped for a month should a case require treatment for so long a time. — Note. The oil may be stirred with a paddle.
